US00D932869S

(12) **United States Design Patent** (10) Patent No.: **US D932,869 S**
(45) Date of Patent: **** Oct. 12, 2021**

(54) **FITTING FOR FURNITURE**

(71) Applicant: **Julius Blum GmbH**, Höchst (AT)

(72) Inventor: **Andreas Holzapfel**, Bregenz (AT)

(73) Assignee: **Julius Blum GmbH**, Hoechst (AT)

(**) Term: **15 Years**

(21) Appl. No.: **35/509,338**

(22) Filed: **Nov. 11, 2019**

(80) **Hague Agreement Data**

Int. Filing Date: **Nov. 11, 2019**

Int. Reg. No.: **DM/205080**

Int. Reg. Date: **Nov. 11, 2019**

Int. Reg. Pub. Date: **May 15, 2020**

(30) **Foreign Application Priority Data**

May 16, 2019 (EM) 006473575

(51) LOC (13) Cl. **08-09**

(52) U.S. Cl.

USPC **D8/323**

(58) **Field of Classification Search**

USPC D8/323, 329, 402

CPC E05Y 2900/20; E05F 1/1058

See application file for complete search history.
